UNITED STATES PATENT OFFICE.

BASIL L. SMITH, OF PHILADELPHIA, PENNSYLVANIA.

STANDARDIZED CLASSIFIED-AD-COPY BLANK.

1,377,855.

Specification of Letters Patent. Patented May 10, 1921.

Application filed July 16, 1918. Serial No. 245,174.

To all whom it may concern:

Be it known that I, BASIL L. SMITH, a citizen of the United States, residing in Philadelphia, Pennsylvania, have invented 5 Standardized Classified-Ad-Copy Blanks, of which the following is a specification.

One object of my invention is to provide a blank or form particularly designed for the use of the classified advertising department 10 of any newspaper, which shall be of such a structure and include such a combination of printed matter with blank spaces as shall primarily render possible the standardization of the operations necessary in connection 15 with the writing, registering, censoring, typesetting, printing, checking, charging, filing, re-soliciting, and charge-collecting of classified advertisements.

A further object of the invention is to 20 provide a blank having the above characteristics, which shall render possible the greatest practicable simplification of, and result in a material reduction in, the labor and equipment required in connection with the 25 work of the classified advertising department of a newspaper;—the invention contemplating such a structure of the blank as will allow of the duplication of certain data as it is being noted by the newspaper 30 employee taking the advertisement, the subsequent separation of the various sections or parts of the blank for use in the various departments of the paper and the ultimate filing of certain or all of said parts for 35 future reference.

These objects and other advantageous ends I attain as hereinafter set forth, reference being had to the accompanying drawings, in which,

40 Figures 1 and 2 are respectively plans of the two sides of an ad-copy blank made in accordance with my invention; and

Fig. 3 is a plan of a modified form of the blank.

45 Referring to the above drawings, the sheet of paper of which each of my ad-copy blanks is formed may be described as consisting of three horizontally elongated main sections, of which that indicated at 1 occupies in the present instance, the lower part 50 of the sheet and is ruled with a series of horizontal lines for the reception of the advertising matter which it is desired to have published in a newspaper or other publication. At the top of this section 1 I preferably print certain directions for the user

of the blank and these in the present instance consist of the words "Write your ad below—want-ad-taker will fill out form above."

60

The data section 2 of my blank occupies, in the present instance, approximately the middle one-third portion of the sheet and consists of two portions 3 and 4, of substantially equal width, respectively to the right and left of a center vertical line. These portions may be described as the bookkeeper's and receipt sections respectively.

The third main section of my blank occupies, in the present instance, approximately the top third of its area, and like the data section, consists of two parts 5 and 6 separated or divided by a line $x-x$ of vertical scoring in continuation of the line x^1-x^2 dividing or defining the two portions 3 and 4 of the data section 2. This top or turn-over section 5—6 is separated from the data section by a line of horizontal scoring $y-y$ so that it may not only be conveniently turned back and over into a position under and immediately adjacent the data section, but may likewise be easily torn or separated therefrom. By reason of the scored $x-x$ line, this turn-over section 85 may also easily be separated into its two parts 5 and 6.

The receipt portion 4 of the data section 3 has three horizontal zones or groups of printed matter 7, 8 and 9 extending across it, in the present instance, from side to side, of which the first or outermost zone, at its left hand end, includes a vertical column 10 of terms indicating the character of the advertisement written in the ad-copy section 95 1. In the case illustrated, this column contains six terms;— "Voluntary," "Solicited," "Local," "Foreign," "Transient," and "Contract," indicating the source and charged rate for the advertisement written below. 100 Next adjacent this column is a narrow column 11 containing three terms indicating the particular issue of the paper in which an advertisement is first to appear, being abbreviations for the words "Morning," 105 "Evening," and "Sunday." Next adjacent the column 11 in the zone 7 is a wider column 12 having three lines or spaces, at one end of which appear the terms "Words," "Lines," and "Inches" respectively, designed 110 to show the volume or space of the advertisement. Between this column 12 and the

- right hand side of the zone 7 are two rectangular spaces 13 and 14 for recording data about the number of insertions and cost of the advertisement. At the top of these spaces are the words "Times" and "Cost," the first space being preferably surrounded by a square figure and having within its lower portion a small square, adjacent which are the words "Broken time."
- 10 The time or calendar zone 8 consists, in the present instance, of four horizontally extending lines 15, 16, 17 and 18 of printed matter for the indicating of the month, days and dates of the printing of the advertisement. The topmost of these contains the customary abbreviations of the names of the months of the year, the lines 16 and 17 contain the numbers 1 to 31 inclusive indicative of the days of the month and, in the 15 present instance, includes also a space in which are the letters "T. F." Uniformly spaced in the line 18 at the bottom of the calendar zone 8 are the abbreviations of the names of the seven days of the week.
- 20 25 The lowest zone 9 of the receipt section is, in the present instance, for designating the classification and indexing term of the advertisement. It has at its right hand end a space 19 inclosed by a rectangular figure, at the top of which is printed the word "Classification" and at the bottom has a relatively smaller rectangular figure adjacent which is the word "General." Between the classification space 19 and the left hand end of 30 the zone 9 is a relatively large space 20 having at its top the designation "Indexing term."
- 35 The bookkeeper's section 3 of my blank furnishes data necessary for entering the 40 charge for the advertisement, and has at the top a relatively broad zone divided into four substantially square spaces 21, 22, 23 and 24 in which are printed the words "Paid," "Charge," "Entered" and "Register" respectively. Below these spaces are four elongated spaces 25, 26, 27 and 28 defined by horizontal ruled lines, of which the first two have at the left hand ends the words "Advertiser" and "Address" respectively, while the two latter in similar positions have printed in them the words "Ad given by" and "Address in ad." At the right hand end of the first of these latter spaces is printed the word "Telephone" and 50 in a similar position in the space 28 are the words "Ad taker."
- 55 Below the space 28, at the bottom of the bookkeeper's section, is a relatively wide elongated space 29 bearing the caption "Instructions to compositor," at the right hand end of which are three smaller elongated rectangular spaces 30, 31 and 32 used in recording data about re-solicitation of the advertisement. Of these the two first contain 60 the words "Results" and "New copy" re-

spectively, while the last contains the words "Reordered" and "Times."

The rear surface of the data section is, in the present instance, preferably provided with a carbon coating in order that any matter written or impressed upon its front face shall be transferred to or duplicated upon a surface engaging it, although as shown in Fig. 3, instead of thus carbonizing the rear face of the data section, I may insert or include between it and the turn-over section 70 5—6, a sheet 50 of carbon paper, and if desirable, may provide lines of scoring, indicated at y^1-y^1 , in order that it may be conveniently torn off and discarded after use. 80

The turn-over section 5—6 has its rear face provided with printed matter identical in substance and arrangement with that on the front face of the data section, so that when turned under the latter by folding it 85 along the line of scoring $y-y$, any particular space or zone of the data section will lie immediately over the corresponding space or zone of the turn-over section.

Under conditions of use the blanks above 90 described are preferably provided in the form of a pad from which they are successively torn or detached as required for use. The employee of a newspaper taking an advertisement "over the counter," writes or 95 permits the advertiser to write, the desired copy or advertisement upon the ruled lines in the space 1 and thereafter notes in the spaces 25 and 26 the name and address of the advertiser, also filling in, if desired, the 100 space 27 either with the telephone number of the advertiser or with the name of his agent. Also on the bookkeeper's section is noted the cost of the advertisement, which if paid for in cash, is inserted in the space 105 21 or if charged, in the space 22. This same amount is also noted in the space 14 of the receipt section;—it being understood that prior to any entry of written material on the data section, the turn-over section 5—6 110 is folded under it so as to receive from the carbon backing duplicate entries of the matter noted on the data section. In the space 28 of the bookkeeper's section is also entered any address given in the advertisement and the name or number of the employee taking the ad.

On the receipt section are entered the instructions given by the advertiser in relation to the dates, the number of times and the issue of the paper in which the advertisement is to appear. For example, if the ad is to appear three consecutive times, the number three is placed in the space 13. If however, it is to appear on days which are not consecutive, a check mark is placed in the rectangular space adjacent the words "Broken time" and one of the terms in the column 11 is marked to indicate the particular issue of the paper in which it is desired 130

that the advertisement shall appear;—in the case indicated, the morning issue. A cross is placed in the line 15 of the time zone 8 to designate the month of the year, one 5 or more of the numbers in the lines 16 and 17 being also crossed or checked to indicate the particular date or dates of the first and last issues of the paper which is to contain the advertisement. Likewise on the line 18, 10 the names of one or more of the days of the week are crossed or checked to correspond to the dates noted in the lines 16 and 17 and in the space 20 is written the particular word or phrase indicating the term under 15 which the particular advertisement in space 1 is indexed or classified. It will be understood that the various possible subjects or heads under which advertisements may be classified are numbered for purposes of 20 convenient reference, preferably in numerical order, and the number of the classification in which any advertisement belongs is placed in the space 19.

Crosses or check marks are also made adjacent 25 one of each adjacent pair of the three pairs of words in the column 10 in order to indicate whether the advertisement is voluntary or solicited, whether it is of local or of foreign origin and whether it is of the 30 transient class or is covered by a previously made contract.

When the above material has been entered on the data sheet together with any ad-style instructions in the space 29, the turn-over section is detached therefrom along the line of scoring $y-y$ and is again torn along the line of scoring $x-x$, the section 6 being then given to the advertiser or his agent as a receipt. The part 5 of the turn-over section 40 is retained by the ad-copy taker. The data and ad-copy sections are delivered first to the register clerk and thereafter are forwarded to the composing room.

As will be obvious to those skilled in the 45 art, with the record provided by the data and ad-copy sections on the one hand and by the bookkeeper's portion 5 of the turn-over section 5—6 on the other, not only is the labor in connection with the bookkeeping 50 and checking of any particular advertisement reduced to a minimum, but any information regarding any particular advertisement may be obtained at any time with the utmost ease after the advertisement 55 blank has once been filled out;—it being understood that after any particular advertisement has appeared in the paper for one or the requisite number of issues and any desired notes made from the data and copy 60 sections belonging thereto, the sheet is placed in a suitable file.

In order to conveniently keep track of the various advertisements, each of the forms is given a register number which is placed 65 in the space 24 of the bookkeeper's section

so that it also appears on the corresponding section of the portion 5. The date of entry of the advertisement is also noted in the space 23, and in case said advertisement is paid for by the advertiser at the time it 70 is delivered to the newspaper office, the section 6 is preferably stamped in any suitable manner to show such payment received.

By my invention the advertiser is given a duplicate of the data required and utilized 75 by the newspaper in displaying his advertisement on any particular day or number of days and this record not only serves as a receipt for the payment of the charge which it indicates but shows both the classification, name and number under which the advertisement will appear in any particular issue of the paper. By reason of this construction and arrangement of the material on the form or blank, the chances of 80 error are reduced to a minimum and all information required for any particular advertisement is concentrated in a form where it may most easily be referred to whenever 85 desired for adjustment of complaints. 90

I claim:

1. A standardized classified ad-copy blank consisting of a sheet formed of three horizontally extending sections, one end section having a portion thereof left blank for 95 the reception of a written ad and the other end section and the middle section each being vertically divided and provided with printed matter to constitute a receipt section and a bookkeeper's section, the said 100 printed matter on the two sections being similar in substance and arrangement but upon opposite faces of the sheet, a dividing line between the latter two sections such that when the end section is folded back 105 thereon against the middle section the corresponding printed matter upon the respective sections is brought into registration, and carbonized material upon the back of the middle section for transferring to the 110 said end section matter written on the middle section when the said end section is folded thereunder.

2. A standardized classified ad-copy blank consisting of a sheet formed of at 115 least two horizontally extending sections of which one is blank and the other is vertically divided and provided with printed matter to constitute a receipt section and a bookkeeper's section; the receipt section 120 having a time zone provided with spaces printed with time indicating symbols and the bookkeeper's section having designated spaces for charges made for data relative to an advertiser. 125

3. A standardized classified ad-copy blank consisting of a sheet formed of three horizontally extending sections, one end section being blank for the reception of a written ad and the other end section and the 130

middle section each being vertically divided and provided with printed matter to constitute a receipt section and a bookkeeper's section, the said printed matter on the two sections being similar in substance and arrangement but upon opposite faces of the sheet, and a line of scoring between the lat-

ter two sections such that when the end section is folded back thereon against the middle section the corresponding printed matter upon the respective sections is brought into registration.

In witness whereof I affix my signature.

BASIL L. SMITH.
